UNITED STATES PATENT OFFICE.

CLIFTON J. PROCTOR, OF HOLMESVILLE, ONTARIO, CANADA.

MOUSETRAP.

Application filed August 21, 1922. Serial No. 583,351.

To all whom it may concern:

Be it known that I, CLIFTON J. PROCTOR, of Holmesville, in the county of Huron, Province of Ontario, Canada, a subject of the King of Great Britain, have invented 5 certain new and useful Improvements in Mousetraps, of which the following is a specification.

This invention relates to traps of the type 10 in which a spring-actuated bail-shaped jaw is hinged on a base and is held in the raised set position by suitable trigger mechanism, and my object is to devise simple means whereby the jaw may be raised and the trigger set without it being necessary to touch either of these parts.

I attain my object by means of the constructions hereinafter described and illustrated in the accompanying drawings in 20 which—

Fig. 1 is a front elevation of my improved mouse trap;

Fig. 2 is a plan view of the same;

Fig. 3 a side elevation, partly broken 25 away, showing the trap set;

Fig. 4 a similar view showing the trap in the set-off position;

Fig. 5 a plan view on an enlarged scale 30 showing the method of supporting the jaw, spring and setting member; and

Fig. 6 a longitudinal section of part of the trap.

In the drawings like numerals of reference indicate corresponding parts in the different figures.

1 is the base, preferably of metal, having an upwardly extending frame member 2 formed on or secured thereto. This frame member is preferably shaped as 40 a guard to prevent animals approaching the bait pan 3 from the rear. The frame 2 at its lower end supports the spindle 4 on which is journalled the jaw 5. This jaw is bail-shaped and has its ends bent to form the coils 6 by means of which it is journalled on the spindle 4 and the rearwardly extending arms 7 which are provided at their outer ends with the hooks 8, which hooks are engaged by the sides of the bail-shaped setting member 9.

At one side the setting member is formed with an eye 10 through which the spindle 4 passes. At the other side of the trap, the side of the setting member is bent and the portion 11 thereof extended alongside the spindle 4 towards the middle thereof. At

the center the portion 11 is bent to form the bail-shaped rock arm 12, the extreme end being preferably formed as an eye 13 encircling the spindle 4. From this construction 60 it follows that the bail-shaped setting member may be rocked to raise the jaw 5 to the position shown in Fig. 3, and thereafter when the jaw is held up as hereinafter described, the bail-shaped member may be returned to the initial position shown in Fig. 4, as its sides are free to disengage themselves from the hooks 8.

The jaw is actuated by a spring which is formed from a continuous piece of wire bent to form the coils 30 located about the spindle 4, the central bail-shaped arm 31 which engages the base, and the two arms 32 which are formed with eyes at their outer ends through which the sides of the bail-shaped jaw pass. It will be noted that the portion 11 of the setting member also passes through one of the coils 30.

The jaw is held in the set position by a trigger-held catch. This catch is preferably formed of wire and is pivoted at its upper end on lugs 14 formed at the upper end of the frame 2. This catch is formed with a shoulder 15 adapted to engage the jaw as shown in Fig. 3, an inclined portion 16 being formed in front of the shoulder so that the jaw may ride over the same and engage the shoulder. The catch is also formed with a depending finger 17 which extends down to a position for engagement with the trigger 18. The catch is also preferably provided with the upwardly extending finger 19 engageable by the jaw after the jaw has passed the inclined portion 16 and the shoulder 15 to rock the catch to its jaw-engaging position in case it fails to do so under the influence of gravity.

The lower end of the finger 19 is preferably formed as a loop 20 embracing the trigger. The trigger is pivoted on the lugs 21, preferably stamped up from the metal of the base, and is provided at its under side with the shoulder 22 having a sloping back adapted to be engaged by the loop 20 to rock the trigger so that the loop may engage in front of the shoulder 22. The bait-pan 3 is preferably formed of channel section with a hole 24 in its upper side to facilitate the baiting of the trap.

The bait pan is pivoted on the lugs 21 and is provided with a laterally extending projection 25. This projection underlies a

rearwardly extending arm 26 which arm is preferably formed of wire integral with the pivot 27 of the trigger and bait pan. Its rearward end 28 is preferably bent into a hook shape form so that it both underlies and overlies the rock arm 12 of the setting member.

The mode of operation of the device is substantially as follows. The setting member 9 normally occupies the position shown in Fig. 4 when the trap is set and retains this position when the trap is set off. To set the trap the setting member is drawn down rearwardly and engages the hooks 8 on the arms 7, thus raising the jaw into engagement with the shoulder 15 of the catch as hereinbefore described. The loop 20 at the lower end of the finger 9 is rocked forward and raises the trigger, engaging in front of the shoulder 22 thereon as hereinbefore described. To enable the trigger to come to the position in which it may engage the loop 20, it is necessary that the bait pan be raised. This is effected by the engagement of the rock arm 12 with the arm 26 which causes the end 28 of the arm 26 to engage the projection 25 and thus lift the bait pan, which allows the trigger to drop to the position shown in Fig. 3. It is then easily lifted by the loop 20 as the latter is swung forward.

It will be seen that after the trap is set, if the bait pan be depressed the trigger will be lifted, the loop 20 disengaged and the catch allowed to rock so that the jaw 5 will ride over the shoulder 22 and be swung down by the action of the spring 30.

What I claim as my invention is:—

1. In a trap, the combination of a base; a spring-actuated jaw hinged thereon; a frame member extending upwardly from the base; a catch pivoted thereon engageable by the jaw and provided with a depending finger; a trigger pivoted on the base and adapted to be rocked by the finger to engage the finger to releasably hold the catch in its jaw engaging position; a pivoted bait pan tending to drop by gravity to release the trigger but permitting the trigger to lift independently for engagement by the finger; a setting member hinged on the base; means whereby the setting member may rock the jaw to its "set" position, and means whereby the setting member, when moved to lift the jaw, raises the bait pan and thus lowers the trigger to its finger engaging position, said

means permitting the said member to return to its initial position independently of the bait pan.

2. A mouse trap constructed as set forth in claim 1 in which the catch for the jaw is provided with a part engageable by the jaw to rock the said finger towards its trigger engaging position.

3. In a trap, the combination of a base; a spring-actuated jaw hinged thereon; a frame member extending upwardly from the base; a catch pivoted thereon directly engageable by the jaw and provided with a depending finger; a trigger mechanism pivoted on the base adapted to be rocked and engaged by the finger to releasably hold the catch in its jaw engaging position; a setting member hinged on the base; and means whereby the setting member may rock the jaw to its "set" position.

4. In a trap, the combination of a base; a spring-actuated jaw hinged thereon; a frame member extending upwardly from the base; a catch pivoted thereon engageable by the jaw and provided with a depending finger; a trigger pivoted on the base and adapted to be rocked by the finger to engage the finger to releasably hold the catch in its jaw engaging position; a pivoted bait pan tending to drop by gravity to release the trigger but permitting the trigger to lift independently for engagement by the finger; and means whereby the setting member, when moved to lift the jaw, raises the bait pan and thus lowers the trigger to its finger engaging position, said means permitting the said member to return to its initial position independently of the bait pan.

5. In a trap, the combination of a base; a spring actuated jaw hinged thereon; catch and trigger mechanism for releasably holding the jaw in its "set" position the catch being directly engageable by the jaw and a setting member adapted to rock the jaw to its "set" position and to directly engage and position the trigger mechanism for engagement by the catch, the catch having a part engageable by the jaw, when raised, to rock the catch to its trigger engaging position.

Signed at Clinton this 31st day of July 1922.

CLIFTON J. PROCTOR.
